UNITED STATES PATENT OFFICE.

GEORGE GETMAN HAKES, OF ILION, NEW YORK.

BROOM OR MOP HOLDER.

1,081,381.

Specification of Letters Patent.

Patented Dec. 16, 1913.

Application filed November 29, 1911. Serial No. 663,078.

To all whom it may concern:

Be it known that I, GEORGE GETMAN HAKES, a citizen of the United States, residing at Ilion, in the county of Herkimer 5 and State of New York, have invented certain new and useful Improvements in Broom or Mop Holders, of which the following is a specification.

This invention relates to holders for 10 brooms, mops and the like.

The object of the invention is to provide a simple, inexpensive, durable and efficient device which may be readily mounted in a kitchen or other place for the support of 15 brooms, mops or similar articles, suspending such articles preferably from the ground against a wall.

With the above and other objects in view the present invention consists in the combination and arrangement of parts hereinafter 20 more fully described, illustrated in the accompanying drawings and particularly pointed out in the appended claim, it being understood that changes may be made in 25 the form, proportion, size and minor details without departing from the spirit or sacrificing any of the advantages of the invention.

In the drawings:—Figure 1 is an elevation 30 of the invention secured to a supporting means illustrating the handle of a broom or mop gripped between the jaws. Fig. 2 is a top plan view. Fig. 3 is a front view partly in section. Fig. 4 is a sectional view 35 through the curved part of the movable jaw.

Referring now more particularly to the accompanying drawings, the reference character 1 indicates a channeled arm formed at one end with a laterally directed extension 40 to provide a fixed jaw 2 whose inner face at its free extremity is preferably beveled as indicated at 2'. In the body of the arm 1 may be formed apertures to receive screws or other suitable fastenings 3 whereby the 45 arm may be secured to a wall or other supporting means with the channeled portion of the arm adjacent the supporting means.

A movable jaw 4 is provided and is preferably curved as indicated. This movable 50 jaw gradually tapers from the inner to the outer edge and has its outer face, between its edges, preferably provided with teeth 5 or otherwise formed to provide a roughened outer surface for the purpose of gripping 55 the handle 6 of the article supported between

the movable and fixed jaws in the manner to be hereinafter explained. This movable jaw has the outer ends of its teeth 5 preferably beveled so as to give the outer edge of the movable member a beveled edge to coöperate 60 with the beveled outer end of the fixed jaw.

The movable jaw 4 is provided with arms 7 and 7', one slightly longer than the other and which converge and terminate in a hub 8 eccentric to the arc of the curved movable 65 jaw through which hub may be passed a suitable pivot 9 which is adapted to pass into the longitudinal slot 10 formed in the arm 1 so that the pivot and consequently the movable jaw may be adjusted longitudinally 70 of the arm 1. To hold the arm firmly in adjusted positions in the slot 10 the pivot 9 is preferably screw threaded at its inner end to receive a nut 11 adapted to be held against rotation in the channeled arm 1 by 75 reason of the flanges of the channel engaging opposite sides of the nut.

It is preferred that the inner side edge of the movable jaw 4 and the arms 7 and 7' do not contact with the outer face of the 80 arm 1 so that there will not be a binding engagement of the movable jaw or the arms 7-7' with the arm 1 upon operation of the jaw. One means for preventing binding engagement of these two elements and to hold 85 them in spaced relation is to dispose one or more washers 12 between the hub 8 and the arm 1 as clearly shown.

The curved jaw 4 is provided with upper and lower laterally directed stops 13 and 14, 90 respectively, which are adapted to engage opposite edges of the arm 1 so as to limit the movements of the movable jaw.

In practice the movable jaw 4 is raised and the handle 6 of the article inserted between the fixed and movable jaws. The movable jaw 4 being eccentrically mounted falls by its own weight or gravity to clamp the handle 6 between the jaws, the engagement of the movable jaw 4 with the handle 105 6, if serrated, facilitating a firm gripping engagement with the handle 6 and by virtue of the outer edges of both jaws being beveled the handle 6 may be readily inserted between the jaws for clamping thereby.

What is claimed is:—

A device of the character described comprising a channeled arm provided with a lateral extension forming a fixed jaw, said arm being also provided with a longitudinal slot, 116

a threaded bolt adjustable within the slot, a nut confined within the channel of the arm for engaging the threaded end of the bolt to secure the latter in adjusted positions in the slot, a movable jaw swingingly mounted on the bolt for coöperation with the fixed jaw, and means for spacing the movable jaw from the arm, the movable jaw having laterally projecting lugs at its ends for engagement

with opposite sides of channeled arm to limit the movement of the movable jaw.

In testimony whereof I affix my signature in presence of two witnesses.

GEORGE GETMAN HAKES.
